Primary Examiner — Michelle E. Wilson*Assistant Examiner* — Clese Moore, Jr.(74) *Attorney, Agent, or Firm* — Michael Best & Friedrich LLP(57) **CLAIM**

We claim the ornamental design for a motorcycle engine air intake, as shown and described.

DESCRIPTION

FIG. 1 is a front perspective view of a motorcycle engine air intake;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a perspective view of the motorcycle engine air intake on a motorcycle.
The broken lines are included for the purpose of showing environment that forms no part of the claimed design.**1 Claim, 9 Drawing Sheets**(56)
